COMBINED CLOCK AND WALL SHELF

John A. Gait, Larchmont, N.Y., assignor to Turner Manufacturing Company, Chicago, Ill., a corporation of Illinois

Application April 21, 1958, Serial No. 50,543

Term of patent 14 years

(Cl. D42—7)

The figure is a perspective view of a combined clock and wall shelf showing my new design.

The top and bottom are conventionally flat and the back is plain and unornamented, while the opposite side is ornamented like the side disclosed.

I claim:

The ornamental design for a combined clock and wall shelf, substantially as shown and described.
